UNITED STATES PATENT OFFICE.

AUGUST FALKEN, OF JAMAICA, NEW YORK.

BOOKMARKER.

Application filed February 25, 1927. Serial No. 170,975.

This invention relates to improvements in book markers.

The primary object of the invention resides in a book marker adapted to be mounted upon the covers of a book and which will automatically mark the pages last exposed upon the closing of the book.

Another object of the invention is the provision of a book marking device which may be removably attached to books of different sizes, so that the same may be removed from one book after being read and applied to another book.

A further object is to provide an automatic book marker which is simple in construction, inexpensive of manufacture and easy to apply or remove from the covers of a book.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a perspective view of my improved book marker in position upon a book and showing the book in an open position.

Figure 2 is a similar view but showing the book in a closed position.

Figure 3 is a vertical sectional view on the line 3—3 of Figure 2.

Figure 4 is a vertical sectional view on the line 4—4 of Figure 1.

Figure 5 is a similar view on the line 5—5 of Figure 1.

Referring more particularly to the drawing, the reference numeral 10 designates a book having rigid front and back covers 11, 11, and bound pages 12 interposed therebetween. My improved book marker is shown in its entirety as at 13 and includes a pair of spring U-shaped clips 14 and 15 which are respectively attached to the top edge of the front and back covers 11. The clips have inwardly extending ears 16 stamped and bent therefrom and to which one end of levers 17 and 18 are respectively pivoted.

The ear 16 of the clip 15 is slotted as at 19 to receive the pivot of the lever 18 to permit of a limited sliding movement of the same for a purpose to be presently explained. The other ends of the levers are connected by a common pivot 20 and to which extension arms 21 and 22 are also pivoted, which

arms are co-extensive with the levers 17 and 18, respectively. The levers 17 and 18 are constructed of a single piece of flat metal bent upon itself to provide a double ply 60 of material, and it is between these plies that the arms 21 and 22 are pivoted so as to permit a limited turning movement of the arms in one direction, as the same abut the closed side of the levers as shown in Figure 65 5 of the drawing.

The free ends of the arms 21 and 22 are provided with openings 23 which receive the reduced portions of T-shaped lugs 24 extending angularly from a pair of plates 25 70 hingedly connected together as at 26. In order to arrange the T-shaped lugs in the openings 23, the cross heads of the lugs are folded upon the body portions thereof and after being passed through the openings are 75 unfolded to their normal position as shown. The cross heads of the T-shaped lugs prevent the lugs from being removed from the openings 23 and provide a loose or flexible joint between the hinged plates and the free 80 ends of the arms 21 and 22.

In practice, the marking device is attached to the book in the manner shown in the drawing, i. e., by passing the clips 14 and 15 over the top edges of the covers 11 where 85 they are held by reason of their springy nature. As the book is opened as shown in Figure 1, the arms 21 and 22 are spread apart which holds the plates 25 out of the path of the pages 12 of the book to permit 90 of the free turning of the pages. Should the book be closed between any two pages which were last exposed, the levers 17 and 18 move inwardly, causing the arms 21 and 22 to close, and in so closing, the same 95 cause the plates 25 to break at the hinged joint 26 and move into flat engagement with each other. As the plates break at their hinged joint, the same will move inwardly between the open pages and serve to mark 100 the pages at which the book was last opened. The slot 19 serves to compensate for a slight movement of the lever 18 when the book is closed from an open position on one side of its center of thickness.

From the foregoing description, it will be seen that I have provided a book marking device which is automatic in its action and which may be removed from one book and applied to another when desired.

While I have described what I deem to be the most desirable embodiment of my in-

vention, it is obvious that many of the details may be varied without in any way departing from the spirit of my invention, and I therefore do not limit myself to the exact details of construction herein set forth nor to anything less than the whole of my invention limited only by the appended claims.

What is claimed as new is:—

- 10 1. In combination with a book having swingingly mounted covers, of a book marking device including attaching clips for supporting the same upon said covers, a pair of pivoted levers respectively pivoted to said clips and a foldable member carried by the free ends of said levers and foldable between the pages of said book upon movement of the covers from an open to a closed position.
- 20 2. In combination with a book having swingingly mounted covers and pages therebetween, of a book marking device, including a pair of clips for attachment to said covers, a member foldable between said pages, and automatic means attached to said clips for unfolding said member out of the path of said pages upon the opening of said book and for folding said member between two adjacent pages upon the closing of said book.
- 30 3. A book marking device comprising attaching clips adapted to be applied to the covers of a book, a foldable member adapted to be moved to a position between two adjacent pages of a book and out of the path of the pages, and automatic means operable upon movement of said attaching clips toward each other for actuating said foldable member.
- 40 4. A book marking device comprising a pair of clips adapted to be received upon the front and back covers of a book, a pair of

levers pivoted to the respective clips and having their free ends pivoted together, arms pivoted to said levers and co-extensive therewith, and a foldable member carried by the free ends of said arms substantially as and for the purpose specified. 45

5. A book marking device comprising a pair of spring clips adapted to be received upon the front and back covers of a book, a pair of levers pivoted to the respective clips and having their free ends pivoted together, arms pivoted to said levers and co-extensive therewith, and a pair of hingedly connected plates carried by the free ends of said arms substantially as and for the purpose specified. 50

6. In a device of the class described, the combination of a book having swingingly mounted covers and pages located between the same, a marker, and connections between said marker and the covers adapted to cause the marker to be inserted between the pages upon movement of the covers toward one another in closing movement of the book, and to withdraw said marker from between the pages when the covers are spread apart to open the book. 55

7. In combination with a book having swingingly mounted covers and pages therebetween, of a book marking device, including means for attachment to said covers, a member movable between said pages, said member being connected to the means for attachment to the covers and automatic means for moving said member out of the path of said pages upon the opening of the book and for moving said member between two adjacent pages upon the closing of said book. 60 75

In testimony whereof I have affixed my signature.

AUGUST FALKEN
